UNITED STATES PATENT OFFICE.

BENJAMIN LIPPER, OF PHILADELPHIA, PENNSYLVANIA, ASSIGNOR TO AUGUSTUS A. LAZARUS, ISAAC A. SCHIWARZ, AND BENJAMIN LIPPER, OF SAME PLACE.

DESIGN FOR DRESS-TRIMMING.

SPECIFICATION forming part of Design No. 21,658, dated June 28, 1892.

Application filed May 31, 1892. Serial No. 436,077. Term of patent 3½ years.

To all whom it may concern:

Be it known that I, BENJAMIN LIPPER, a citizen of the United States, and a resident of Philadelphia, Pennsylvania, have invented a new and original Design for a Dress-Trimming, of which the following is a specification.

My design is fully shown in the accompanying drawing, which represents a face view of a piece of the trimming.

The design comprises the central tape-like band or ribbon *a*, adjacent to each edge of which is a narrow band *b*, and passing back and forth across the face of the band *a* is a cord *d*, which forms loops, first beyond one edge and then beyond the other edge of the said band. Between these loops are projecting fan-shaped figures *f*, which join each other

beyond the loops, and across these fan-shaped figures extend bands *g*, while projecting inwardly from the bases of said fan-shaped figures, so as to overlie the central band *a*, are loops *i*.

I claim—

The design for a dress-trimming, substantially as described, and as shown in the accompanying drawing.

In testimony whereof I have signed my name to this specification in the presence of two subscribing witnesses.

BENJAMIN LIPPER.
